LEAF STEMMER

Joseph Gough, Newark, N. J., assignor to Gough
Stemming Machine Corporation, New York,
N. Y., a corporation of New Jersey

Application October 29, 1932, Serial No. 640,141

16 Claims. (Cl. 131—57)

The invention relates to stemming machines, that is to say, to machines for extracting the stems or large central veins from the blades of leaves, such as are employed for stemming tobacco leaves for example.

Herein the word "stem" is employed as including so much of the long central vein or rib of a leaf as is removed from the blade in the "stemming" operation.

10 A strip (or strips) of card clothing is a desirable device to strip the leaf blades from the stems. A considerable amount of power is required to drive the card clothing however, especially where the stemming machine is of the continuously acting type wherein the leaves are stemmed while in movement through the machine; in machines of the latter type the card clothing is called on to propel the leaves through the stemming station against a considerable opposing force. In order 15 to drive the card clothing it has been the practice heretofore to attach the strip of card clothing to one edge of a wide belt, the width of this carrying belt and the corresponding width of the face of the driving pulley enabling the latter to drive the belt, and hence the card clothing, without undue slipping. This practice is not entirely satisfactory however. Considerable time is required to replace a worn or damaged card clothing mounted in this manner. Further, with use 20 of the card clothing tends to depart from its intended path or position at the stemming station. This seems to be due principally to the fact that the wide carrying belt stretches unevenly, so that the edge of the wide belt takes a 25 wavy shape as viewed looking straight toward the faces of the wide belt and the card clothing; in part too the fault may be due to the fact that the stresses tend to stretch the card clothing more than its carrying belt in passing around the pulleys, 30 and thus tend to cause the card clothing to buckle in the straight runs of the belt and card clothing. Still further, devices working close beside the teeth of the card clothing are used to remove the blades caught in the teeth; commonly for this 35 purpose a wire or the like is laid in a space provided for it in the midst of the teeth of the clothing. The departure of the card clothing from its initial position or path interferes with the functioning of this wire or other device employed to remove the blades from the card clothing, and may bring this device against the card clothing teeth in such a way as to bend the teeth.

50 My invention avoids these faults and provides a blade-stripper of the card-clothing type that remains permanently in its initial and intended

path or position, and permanently in the desired relation to the devices with which it cooperates, and provides an arrangement wherein worn portions of the stripper, large or small, can be repaired quickly, easily and cheaply. This is accomplished, in brief, by the transverse division of the card clothing or analogous toothed stripping element into a number of separate sections or pieces, and the fastening of these sections individually to individual points on the carrying device between which the major part or the whole of the flexure of the carrying device occurs as the latter passes around a pulley or other support; and preferably by using also such a narrow supporting and driving belt or other carrying device for the sectionalized card clothing that any stretch or wear tending to lengthen the carrying device as it were, occurs substantially uniformly throughout its width; for example, the width of this carrying belt or other device may approximate the width of the card clothing. Preferably a chain belt is employed as the driving and carrying device, and each piece or section of the card clothing or other toothed element is mounted on a single link of the chain; a chain and toothed driving pulley for the chain will give adequate power to drive the card clothing. A rigid surface or rigid surfaces will give all the support against bending at the stemming station that card clothing or like flexible-backed toothed strippers may need; preferably one such rigid surface is provided for each toothed stripping section, these being mounted on or constituting parts of the carrying device and bearing the sections of the toothed element; but rather than employ links of the chain or other elements of the carrying device for this purpose however, I prefer to employ members additional to the chain proper to support the toothed stripping sections against forced bending, these members being attached individually to the carrying device. By mounting the individual sections of the toothed stripping element on the carrying device in a manner permitting ready removal, any individual section that may fail or become worn is readily replaced. By locating underneath the table top, leaf feeder, or the like, any pulley or other support around which such a chain of toothed stripping sections may pass between the stemming station and the entrance end of the machine, the leaves may be fed to the stripper at a point thereon where the sections occupy substantially the same relative positions to each other that they occupy at the stemming station, and thus the stripper

prevented from grasping the leaves between adjacent sections of it.

These and other matters concerned with the invention appear from the stemming machine 5 illustrated somewhat diagrammatically in the accompanying drawing, in which Fig. 1 is a sectional elevation of the machine at the stemming station; Fig. 2 is a plan view of the construction shown in Fig. 1; Fig. 3, drawn to a larger scale, 10 is an elevation of the stripper chain of the machine of Fig. 1; Fig. 4 is a vertical section on the line IV-IV of Fig. 3, and Fig. 5 is a plan view of one section of the card clothing of Figs. 1 and 3, and adjacent parts of the chain.

15 The machine illustrated is of a known type, and substantially only so much of it is shown as is necessary to an understanding of the invention. The horizontal table top 1 is to receive the leaves at the left hand end and generally support them 20 as they travel through the machine. The mechanism or device for grasping the stems also pulls the stems from the blades while the latter are retained by the blade stripper. Essentially it 25 consists of a pair of cooperating belts 2 and 3 carried respectively by rollers 4 and 5 and another pair of rollers not shown, but as will be understood from the drawing. These belts 2 and 3 receive the butt ends of the stems between themselves and are driven in such a direction that 30 they pull the stem away from the blade stripper (upwardly in Fig. 2). It will be understood of course that my invention is not limited to the particular device 2-3 here employed to grasp the stems, nor to the particular arrangement of 35 the stem-grasper and blade-stripper whereby the stem and blade are pulled apart from each other.

The blade stripper comprises a sprocket chain belt (Fig. 1) and a plurality of sections 6 of card clothing (one section being illustrated in 40 Fig. 5), each mounted on one of the blocks 7 of the chain as shown most clearly in Figs. 3, 4 and 5. The links connecting the blocks appear 45 at 8. The chain may be mounted on two toothed or sprocket wheels 20 and 21 carried by the machine frame; one of these, say the sprocket 21, may be power driven to propel the stripper in the direction shown by the arrow in Fig. 1. Flexure of the chain in passing around the supports 20 and 21, occurs at the pivots between the blocks 50 7 and links 8 of course. Hence by dividing the card clothing into sections 6 and fastening each to only one block or link of the chain, all tendency to stretch the card clothing in passing around the belt supports 20 and 21 has been eliminated. To mount the sections 6 on the blocks 55 of the chain, I prefer to secure them to carriers 12 separate from and secured to the chain. These carriers may be made as illustrated in the drawing. Primarily each carrier 12 provides a flat or plane base against which the flexible fabric of the card clothing lies (Fig. 4). To mount the sections on the carriers, each may be recessed 60 to form a box as illustrated best in Fig. 4; the recess is provided with an overhanging lip 13 along one side, and a second overhanging lip 14 along the other side, these lips serving to retain the card clothing 6 in the carrier. Preferably one of 65 these lips is removable from the box or carrier; for example, the lip 14 may consist of a relatively thin flat bar fastened to the box side by a machine screw or screws 15; this permits a new piece or section 6 to be substituted quickly for a worn one. Obviously the boxes 12 may be attached to the chain in various ways; conveniently 70 each is attached to a single block 7 by a single

75 screw 16 in co-operation with a projection or projections, for example a lip 17 on the box, extending over the outside face of the adjacent chain links 8; the screw 16 holds each box to its chain block while the projection or projections 17 prevent the box from turning on the single screw. Preferably the chain is a double chain, that is to say, is made up of pairs of blocks 7 arranged side by side, and the toothed wheels or sprockets 20 and 21 are provided with two rows of cooperating teeth; this, however, is simply to drive the chain with sufficient power, and obviously is subject to modification. Underneath the chain at the stemming station a rigid surface may be provided by the table top 1 or otherwise to prevent 15 the chain flexing undesirably under the stresses imposed on the card clothing by the leaves.

A plate 23 in effect extends the table top 1 over the pulley or sprocket 20 which is between the stemming station and the entrance end of 20 the machine, so that the leaves first reach the sectionalized card clothing at a point 24 where the card clothing sections constitute a continuous strip or strips of card clothing; this prevents leaves entering between adjacent sections of the 25 card clothing while the latter are separated as they are (say at 25) where they pass around a pulley or sprocket. The wire 26, fastened to the table toward the entrance end of the machine (Figs. 1 and 2) and resting in a longitudinal 30 space provided between the teeth of the card clothing (Figs. 4 and 5) provides for separating from the sectionalized card clothing any stemmed blades that may be caught in the teeth; thus as the card clothing passes downwardly 35 around the pulley or sprocket 21 this wire 26 holds the blades up while the card clothing passes away from them; these blades then fall from the wire. Obviously other or additional devices 40 may be employed to separate the blades from the lower card clothing; the wire 26 is illustrative of any device for this purpose, as well as illustrative of a device preferably employed. Preferably I use a second belt 29 of card clothing to confine the leaves in the lower or sectionalized card 45 clothing belt at the stemming station. Anything that will serve this purpose may be substituted for this second card clothing belt 29 however.

The stem puller 2-3 in the machine illustrated is so located (its bite being somewhat below 50 the level of the tops of the teeth of the sectionalized card clothing in the upper run of the latter), that the lower card clothing serves as the blade stripper substantially alone; that is to say, the stems are drawn somewhat downwardly and thus between the teeth of this sectionalized card clothing. Under these circumstances, little power is required to drive a second card clothing belt, such as 29; ordinarily its teeth slightly engage between the teeth of the lower card clothing belt, and in instances I have dispensed entirely with separate driving means for such an upper belt, allowing it to be driven simply by its frictional engagement with the lower card clothing. Under these circumstances it is not necessary to divide this upper card clothing 29 into sections like the lower card clothing; in other words, this upper card clothing belt 29 may be simply a continuous strip of card clothing carried on loose-running pulleys 30 for example. 60 65

To partially support the blades, especially as they approach the stemming station (opposite the stem puller 2-3), and thus to help to carry the leaves into the stemming station, I usually employ one or more belts 31 running parallel in 70 75

the same direction and at about the same level as the sectionalized card clothing. These may be smooth surfaced belts. Such a belt (or belts) is driven of course, at the same speed as the sectionalized card clothing; it or they may be mounted on a loose running pulley 32 for example, and on a driven pulley 33 which, for convenience, may be mounted on and fast to the shaft 34 which carries and by means of which the pulley or sprocket 21 of the sectionalized card clothing is driven.

The operation of the machine illustrated will be rather apparent: The operator feeds the leaves, more or less one by one, onto the sectionalized card clothing and the auxiliary conveyor belt 31 about at 24; the leaves are fed with their blades lying on the auxiliary conveyor belt 31, and with their butts extending somewhat to the opposite side of the sectionalized card clothing so 10 as to be within the reach of the stem-grasping mechanism, e. g. the pair of belts 2 and 3, as they approach the latter. The card clothing belts and the auxiliary conveyor belt 31 being driven, say, continuously, the leaves are conveyed in this position until the butts enter the bite between the belts 2 and 3; these thereupon pull the stems to the rear of the machine (upwardly in Fig. 2), but since the blades cannot follow through the teeth of the card clothing, 15 each blade is more or less bunched up against the card clothing, and particularly the lower card clothing. The stemmed blades continue with the card clothing belts therefore, to the right in Figs. 1 and 2, and as the lower card clothing belt passes downwardly around the pulley or sprocket 21, the stemmed blades fall to the floor, those strongly entangled with the lower card clothing being forced off it by their travel above the wire 26.

It will be understood that my invention is not limited to the details of construction described herein and illustrated in the accompanying drawing, except as appears hereinafter in the claims.

I claim:

1. In a stemming machine having means to grasp the stems, the combination of a plurality of sections of card clothing, a flexible carrying device to carry said plurality of card clothing sections opposite said stem-grasping means, and means to fasten the sections of card clothing individually to individual points on said carrying device between which the carrying device can flex.

2. In a stemming machine having means to grasp the stems, the combination of a plurality of sections of card clothing, a flexible carrying device to carry said plurality of card clothing sections opposite said stem-grasping means, and means releasably fastening said sections of card clothing to said carrying device.

3. In a stemming machine having means to grasp the stems, the combination of a plurality of sections of card clothing, a flexible carrying device to carry said plurality of card clothing sections opposite said stem-grasping means, and means releasably fastening said sections of card clothing individually to individual points on said carrying device between which the carrying device can flex.

4. In a stemming machine having means to grasp the stems, the combination of a blade-stripping device divided into a plurality of sections each including a flexible base and teeth projecting from the base, a flexible carrying de-

vice for said sections, means to fasten the sections individually to individual points on said carrying device between which the carrying device can flex, and means to support said flexible bases of said sections, throughout substantially the whole area of each, opposite said stem-grasping means.

5. In a stemming machine having means to grasp the stems, the combination of a blade-stripping device having a flexible base and teeth projecting therefrom, said blade-stripping device being divided into a plurality of sections, and means to carry and support said sections including a flexible carrying device having rigid means, engageable with the flexible bases of said sections throughout substantially the whole of the area of each, and means to fasten said sections individually to individual points on said flexible carrying device between which the carrying device can flex.

6. In a stemming machine having means to grasp the stems, the combination of a blade-stripping device including a flexible base and teeth projecting therefrom, said blade stripping device being divided into a plurality of sections, a flexible carrying device to carry said plurality of sections, and a plurality of rigid supports attached to said flexible carrying device, said sections being attached one to each of said rigid supports.

7. The subject matter of claim 6 characterized by the fact that said rigid supports consist of boxes, each box having means to removably hold one of said sections within the box.

8. The subject matter of claim 6 characterized by the fact that said flexible carrying device is a chain, and that each of said rigid supports comprises a box having means to releasably hold one of said sections in the box.

9. In a stemming machine having means to grasp the stems, the combination of a blade-stripping device having a base portion and spaced projecting teeth, substantially at right angles to said base portion, to strip the blades from the stems, means to work beside said teeth to remove blades from said teeth, said blade-stripping device being divided into sections, and a narrow flexible carrying device to carry said plurality of sections.

10. The subject matter of claim 9 characterized by the fact that said means to remove blades from said teeth is a substantially rigid member along which the said teeth pass.

11. In a stemming machine having means to grasp the stems, the combination of a chain belt, a plurality of sections of a blade-stripping device attached to and carried by said chain, each of said sections having teeth spaced from each other and projecting substantially at right angles from the face of said belt to strip the blades from the stems, and means to work in the midst of said teeth to remove blades from said teeth.

12. In a stemming machine having means to grasp the stems, the combination of a chain belt, means to drive said chain belt continuously, a plurality of sections of a blade stripping device attached to and carried by said chain, each of said sections having teeth spaced from each other and projecting substantially at right angles from the face of said belt to strip the blades from the stems, and means to work close beside said teeth to remove blades from said teeth.

13. In a stemming machine having means to grasp the stems, the combination of a blade-stripping device divided into a plurality of sections,

5

- a belt, means to carry the belt, means to fasten said sections individually to individual points on said belt between which the belt can flex in passing around said belt-carrying means, and
- 5 means to support the leaves, substantially out of the reach of the blade-stripping device, in passing over such of said belt-carrying means as are located between said stem-grasping means and the entrance end of the machine, to cause the
- 10 leaves to be delivered to said blade-stripping device at a point thereon where the sections thereof occupy substantially the same relative positions as they occupy when passing said means to grasp the stems.
- 15 14. In a stemming machine having means to grasp the stems, the combination of a plurality of sections of card clothing, a flexible belt to carry said plurality of card clothing sections, means to fasten the sections of said card clothing
- 5 individually to individual points on said belt between which the belt can flex, said stem-grasping means being so related to said card clothing that said stem-grasping means tends to draw the stems toward the bases of the wires of the card clothing, and a continuous belt of card clothing to retain the leaves in the first mentioned card clothing.
15. In a stemming machine having means to grasp the stems, the combination of a plurality of sections of card clothing, and a metallic chain 10 belt to carry said plurality of card clothing sections past said means to grasp the stems incorporating blade-stripping relation thereto, said card clothing sections being arranged successively on said belt and being fastened thereto. 15
16. The subject matter of claim 15 characterized by the fact that each of said sections is fastened to a single rigid element of said chain.

JOSEPH GOUGH.
